APPARATUS FOR CLEARING TUBES IN
THE HEAD

Dennis H. Dwyer, Detroit, Mich.

Application July 11, 1949, Serial No. 104,125

7 Claims. (Cl. 128—184)

1

The present invention relates to apparatus for clearing tubes in the head.

It is an object of the present invention to provide apparatus adapted to establish air pressure in tubes of the head sufficient to clear such tubes.

It is a further object of the present invention to provide apparatus comprising a pair of nose pieces or plugs adapted to fit in the nostrils of the user and to establish a tight seal therewith, one of the plugs being connected to a source of air pressure and the other of said plugs being imperforate.

It is a further object of the present invention to provide apparatus of the character described characterized by a configuration of the nose piece and plugs such that they substantially fill the nostrils of the user.

Other objects and features of the invention will become apparent as the description proceeds, especially when taken in conjunction with the accompanying drawings, wherein:

Figure 1 is a perspective view of the apparatus.

Figure 2 is a front elevation thereof.

Figure 3 is a fragmentary view illustrating a modified construction.

Referring now to the figures there is illustrated the apparatus for clearing the tubes of the head. This apparatus comprises a pair of nose pieces or plugs 10 and 12, associated with a rubber bulb or the like 14 for establishing pressure. Interconnecting the bulb 14 and one of the plugs as for example the plug 10, is an air conduit 16. The plug 10 has an air outlet opening 17 in its end. Conveniently, the air conduit 16 may be associated with a second conduit 18 having an inlet connection 20 for use with a medication, if such is desired. The down-turned tube 20 extends through a cap 22 which may serve as a closure for the bottle 24 containing medication. The end of the tube 18 located within the plug 10 is associated with the end of the tube 16 such that the air blast from the tube 16 establishes suction and withdraws medication from the bottle. Alternatively the device may be used without medication and accordingly, tube 18 and associated parts may be omitted.

The plug 12 is structurally connected by a support rod 26 to the tube 16. However the plug 12 is imperforate and its function is to close one of the nostrils of the user while air is introduced into the other nostril through the plug 10.

It is important that the nose pieces 10 and 12 be sufficiently large so as to establish a strong airtight seal. Moreover, it is desirable for the

2

nose pieces 10 and 12 to have tapered forwardly extending portions which will substantially fill the interior of the nostrils. This avoids the presence of air chambers in which the air introduced through the nose piece 10 could expand and materially, it enhances the effectiveness of the device in opening and clearing tubes such as the eustachian tubes in communication with the nostrils.

10 In the use of the device it is important to close the passages connecting the throat to the nose and this may be accomplished by the user swallowing after the device is used. Best results are obtained when the bulb 14 is compressed during 15 the act of swallowing so that the resultant air pressure cannot escape into the throat of the user.

Figure 3 illustrates a modified construction in which the dummy plug 12 is mounted to one of the tubes 16 or 18 for swinging movement thereabout so that the plug 12 may assume a position at one side or the other of the plug 10. The detail of this construction is that without inverting the bottle 24 connected to the apparatus, the apertured plug 10 may be used in either the right or the left nostril. As indicated in Figure 3 the plug 12 is shown as carried by an arm 30 having an eye or swivel connection 32 embracing one of the tubes 16 or 18 (the tube 18 in the embodiment illustrated). Intermediate its end the rod or arm 30 may if desired be provided with a recessed portion 34 adapted to engage the other tube 16 when the plug 12 is swung from the full line position illustrated to the dotted line position. At the same time, at the opposite side of the swivel connection 32 there may be provided an extension 36 shaped to engage the underside of the tube 16. This construction provides for proper location of the nose piece 12 in a position at either side of the other nose piece, and in addition permits use of the apparatus to apply air pressure to either nostril without inverting the medication bottle.

45 It will be understood that in the embodiment illustrated in Figure 3 the tubes 16 and 18 may if desired be perfectly straight, the tube 16 which communicates with the bulb 14 in such case being in alignment with the air bulb 14.

The drawings and the foregoing specification constitute a description of the improved apparatus for clearing tubes in the head in such full, clear, concise and exact terms as to enable any person skilled in the art to practice the invention, the scope of which is indicated by the appended 50 claims.

What I claim as my invention is:

1. Apparatus for clearing tubes comprising an air bulb, a pair of plugs of a size to completely fill the nostrils of the user and to establish an airtight seal therewith, one of said plugs having an air discharge opening in the end thereof, the other of said plugs being impervious to air, and an air passage connecting said bulb to the air discharge opening in the said one plug.

2. Apparatus as defined in claim 1 in which said plugs are elongated and tapered to have forwardly extending portions substantially filling the interior of the nostrils.

3. Apparatus for clearing tubes comprising a first nose piece having an air discharge opening in the end thereof, a pressure bulb, an air tube leading from said bulb to said nose piece, a second tube having a cap thereon for connection to a medication bottle, said second tube entering said nose piece and associated with said first tube to deliver medication into said nose piece, a dummy imperforate nose piece, means mounting said dummy nose piece in properly spaced relation to provide for simultaneous insertion of both nose pieces into the nostrils of the user.

4. Apparatus as defined in claim 3 in which

said means supporting said dummy nose piece is pivoted to provide swinging said dummy nose piece from one side to the other of said first nose piece.

5. Apparatus as defined in claim 3 in which said means supporting said dummy nose piece comprises a pivot mounting secured to one of said tubes.

6. Apparatus as defined in claim 5 in which said pivot mounting comprises stop means cooperating with the other of said tubes to position said dummy nose piece selectively at either side of said first nose piece.

7. Apparatus for clearing tubes in the head 15 with medicated air comprising a pair of plugs spaced apart to enter the nostrils of a user simultaneously, said plugs being sufficiently large to form an airtight seal with the nostrils, one of said plugs being imperforate, the other of said plugs having means for discharging medicated air 20 therethrough under elevated pressure into the nostrils of the user.
